J. E. STARNES,
SPARK ARRESTER.

APPLICATION FILED AUG. 15, 1917. RENEWED JAN. 25, 1919.

1,312,761.

Patented Aug. 12, 1919.

UNITED STATES PATENT OFFICE.

JOSEPH E. STARNES, OF LIVE OAK, FLORIDA.

SPARK-ARRESTER.

1,312,761.

Specification of Letters Patent.

Patented Aug. 12, 1919.

Application filed August 15, 1917, Serial No. 186,400. Renewed January 25, 1919. Serial No. 273,173.

To all whom it may concern:

Be it known that I, JOSEPH E. STARNES, a citizen of the United States, residing at Live Oak, in the county of Suwanee and State of Florida, have invented certain new and useful Improvements in Spark-Arresters, of which the following is a specification, reference being had to the accompanying drawings.

10 This invention relates to certain improvements in spark arresters and has relation more particularly to a device of this general character especially designed and adapted for use in connection with wood fuel, and it 15 is an object of the invention to provide a novel and improved device of this general character including a horizontally disposed perforate partition intersecting the smoke box together with a tubular perforate member arranged within the stack or flue and 20 wherein said member is substantially in the form of a truncated cone.

The invention also has for an object to provide a device of this general character 25 wherein the perforate member within the stack can be adjusted thereby to facilitate the discharge of smoke at the starting of the fire and also wherein the horizontal partition is provided with a hinged portion 30 adapted to be opened at the starting of the fire to facilitate the discharge of the products of combustion.

The invention consists in the details of construction and in the combination and arrangement of the several parts of my improved spark arrester wherein certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood I will now proceed to describe the same with reference to the accompanying drawings wherein,

Figure 1 is a fragmentary view in elevation illustrating an engine boiler together with manual means for imparting movement to my improved spark arrester as herein embodied;

Fig. 2 is an enlarged fragmentary sec-

tional view illustrating in detail my improved spark arrester as herein embodied;

Fig. 3 is a fragmentary view in elevation illustrating a modified form of my invention; and

Fig. 4 is an enlarged fragmentary view partly in elevation and partly in section of the operating cylinder as employed in the invention as disclosed in Fig. 3.

As herein disclosed B denotes a boiler of any preferred type provided at its forward end with a smoke box S having in communication therewith the upstanding flue or stack F. 1 denotes a draft sheet carried by the flue sheet 2 and extending within the smoke box S. Suitably secured to the draft sheet 1 and to the front and side walls of the smoke box S is a perforate partition P preferably formed of reticulated fabric of a predetermined mesh. It is also to be noted that the partition P is positioned slightly below the exit nozzle N for creating the requisite draft in a manner and for a purpose believed to be clearly apparent to those skilled in the art to which my invention pertains. The partition P is provided with a transversely disposed hinged section 3 80 preferably positioned in advance of the nozzle N and which is adapted to be adjusted vertically into an open position at the starting of a fire to facilitate the escape of the products of combustion. At this time it 85 may be well to state that my invention as herein embodied is particularly well adapted for use in connection with wood as a fuel. After the fire has started the section 3 is 90 shut into a closed position and it will be self evident that the heavy particles or sparks will be arrested by the partition P.

It has also been found of utmost importance in practice to apply within the flue or stack F a perforate member M formed preferably of reticulated material of predetermined mesh and which member is tubular with its opposite ends open and substantially in the form of a truncated cone with its smaller end disposed downwardly. The member M extends within the upper portion of the flue or stack F and when in its lower position contacts with the wall of said flue or stack at the top thereof. The draft created by the nozzle N will cause the finer sparks or particles to pass through the parti-

tion P toward the sides of the flue or stack F and said finer sparks or particles are prevented from escaping through the upper end of the flue or stack F by the member M. Intersecting the smoke box S is a horizontal shaft 4 disposed transversely thereof and which is provided with the oppositely directed rock arms 5 and 6. Pivotally engaged with the free end portion of the inwardly directed rock arm 5 is the lower end portion of the vertically disposed rod 7 extending upwardly through the flue or stack F and secured as at 8 to the lower end portion of the member M. Co-acting with the member M and the rod 7 is the brace rod 9. The outer or free end portion of the forwardly directed rock arm 6 has pivotally engaged therewith the rod 10 which is also operatively engaged with the outer or free margin of the pivoted section 3 of the partition B. In view of the foregoing it will be at once self evident that when the shaft 4 is rocked to swing the section 3 downwardly into an open position the rod 7 will be moved upwardly to raise the member M free of the flue or stack F so that the products of combustion may have free egress from within the smoke box S. Upon reverse movement of the shaft 4 the section 3 will be returned to closed position and the member M lowered into applied position within the flue or stack F. Requisite rocking movement will be imparted to the shaft 4 when desired but it is preferred that a portion of the shaft 4 extend exteriorly of the smoke box S and be provided with the upstanding rock arm 11 having pivotally engaged therewith a rod 12 extending rearwardly of the boiler and operatively engaged with the lever 14 of a conventional type.

In the form of my invention as particularly illustrated in Fig. 4 the hinged section 3 and the member M are caused to intermittently open and close during the operation of the locomotive and as is particularly illustrated in Fig. 4 the rock arm 11^a has operatively engaged therewith the rod 15 pivotally engaged with the piston rod 16 extending within the cylinder C and coacting with the piston 17 arranged for reciprocatory movement within the cylinder C. The cylinder C is suitably supported exteriorly of the smoke box S. In communication with the interior of the cylinder C through the head thereof remote from the rod 16 is a steam line 18 leading from the steam chest 19 and the steam is emitted into and exhausted from the cylinder C through the chest 19 under the influence of the conventional relief (not shown) coacting within the valve 20. The piston 17 is retracted under the influence of the expandable member 21 interposed between the piston 17 and the head of the cylinder remote from the

line 18. As particularly illustrated in Fig. 4 the expandable member 21 comprises a conventional coil spring surrounding the rod 16.

Depending from the upper marginal portion of the member M are the arms or fingers 22 which contact with the inner wall of the flue F and serve as guides for the member M. It is to be understood that the arms or fingers 22 are of a length greater than the extent of movement of the member M so that said arms or fingers are at all times in operative engagement with the flue F.

From the foregoing description, it is thought to be obvious that a spark arrester constructed in accordance with my invention is particularly well adapted for use by reason of the convenience and facility with which it may be assembled and operated and it will also be obvious that my invention is susceptible of some change and modification without materially departing from the appearance and spirit thereof and for this reason I do not wish to be understood as limiting myself to the precise arrangement and formation of the several parts herein shown in carrying out my invention in practice except as hereinafter claimed.

I claim:

1. In combination with a smoke box having a flue in communication therewith, a perforate partition intersecting the smoke box and provided with a swinging section, a tubular member in the form of an inverted truncated cone extending within the outer end portion of the stack and having its opposite ends open, the walls of said member being perforate, and means co-acting with the member and the swinging section of the partition for moving the member outwardly of the stack when the swinging member is adjusted into open position.

2. In combination with a smoke box having a flue in communication therewith, a perforate tubular member extending within said flue and in the form of an inverted truncated cone, and pressure operated means for reciprocating the member longitudinally of the flue.

3. In combination with a smoke stack, a perforate tubular member extending within the stack through the outer end thereof, said tubular member being in the form of an inverted truncated cone, means for imparting movement to the tubular member longitudinally of the stack, and elongated arms depending from the upper portion of the tubular member and frictionally engaging the inner wall of the stack to afford guiding means for the member in its movements, said arms being independent of the means for moving the member.

4. In combination with a smoke box having a flue in communication therewith, a tubular member extending within said flue

and in the form of an inverted truncated cone, means for imparting movement to said member longitudinally of the flue, and arms depending from the outer marginal portion 5 of the member and having sliding contact with the inner wall of the flue to afford guiding means for the member in its movement, said arms being independent of the means for moving the member.

10 5. In combination with a smoke stack having a flue in communication therewith, a perforate tubular member extending within the flue through the outer end thereof, said flue being in the form of an inverted truncated 15 cone and open at opposite ends, a rod engaged with the inner end of the tubular member and extending through the stack into the smoke box, a shaft intersecting the smoke box, and extending exteriorly thereof, 20 a rock arm carried by the shaft and operatively connected with the lower end of the rod, and means coacting with the extended portion of the shaft for rocking the same to move the tubular member longitudinally of 25 the flue.

6. In combination with a smoke stack having a flue in communication therewith, a perforate tubular member extending within the flue through the outer end thereof, said flue 30 being in the form of an inverted truncated cone and open at opposite ends, a rod engaged with the inner end of the tubular member and extending through the stack into the smoke box, a shaft intersecting the smoke box, and extending exteriorly thereof, 35 a rock arm carried by the shaft and operatively connected with the lower end of the

rod, and expansion means coacting with the extended portion of the shaft for intermittently rocking the same for moving the tubular member toward and from the outer 40 end of the flue.

7. In combination with a smoke box and a steam chest of an engine, a tubular member extending within said flue and in the form 45 of an inverted truncated cone, a rock shaft, an operative connection between the rock shaft and the member for moving said member longitudinally of the flue, a piston with- 50 in the cylinder and operatively connected with the rock shaft, and a communication between the steam chest and the cylinder for imparting movement to the piston.

8. In combination with a smoke box and a steam chest of an engine, a tubular member 55 extending within said flue and in the form of an inverted truncated cone, a rock shaft, an operative connection between the rock shaft and the member for moving said member longitudinally of the flue, a piston with- 60 in the cylinder and operatively connected with the rock shaft, a communication be- 65 tween the steam chest and the cylinder for imparting movement to the piston in one direction, and automatic means for impart- ing movement to the piston in the opposite direction.

In testimony whereof I hereunto affix my signature in the presence of two witnesses.

JOSEPH E. STARNES.
